UNITED STATES PATENT OFFICE.

JOHN H. MAURER, OF LONG BEACH, CALIFORNIA.

COMBINATION FASTENER.

Application filed March 4, 1927. Serial No. 172,733.

This invention relates to door stops and aims to provide novel means whereby a door may be held in a partially opened position, eliminating any possibility of the door being closed accidentally.

An important object of the invention is to provide a device of this character which will efficiently act as a door check, and one which will be invisible when not in use, to 10 the end that the door check will not in any way mar the beauty, or break the lines of the door to which the check is secured.

With the foregoing and other objects in view which will appear as the description 15 proceeds, the invention resides in the combination and arrangement of parts and in the details of construction hereinafter described and claimed, it being understood that changes in the precise embodiment of the invention herein disclosed, may be made within 20 the scope of what is claimed, without departing from the spirit of the invention.

Referring to the drawings:

Figure 1 is a perspective view illustrating 25 a door equipped with a check constructed in accordance with the invention, the check being moved to its active position.

Figure 2 is a perspective view of the control arm connected with the check.

Figure 3 is a fragmental sectional view 30 through one portion of the door, showing the check in its inactive position.

Figure 4 is a fragmental front elevational view of a door and check.

Figure 5 is a fragmental perspective view 35 illustrating one end of the door check.

Figure 6 is a perspective view illustrating a door check made of a single length of metal.

Figure 7 is a sectional view through a portion 40 of a door and illustrating a modified form of the invention.

Figure 8 is a perspective view of the modified form of the invention, the barrel there- 45 of being partly broken away.

Referring to the drawings in detail, the reference character 5 indicates a door, which is of the usual construction, and which has its forward lower edge cut away as clearly 50 shown by Figure 8 to provide a groove 6 and a compartment 7 in which the door check forming the essence of the present invention is positioned.

The door check includes a main or body 55 portion 8 constructed of a length of spring metal, one end thereof being secured within

a groove formed in the lower edge of the door, the forward end of the body portion 8, terminating at a point adjacent to the front edge of the door where it is supplied with a 60 pad 10 constructed of rubber or other friction material.

The reference character 11 indicates a spring arm that has a right angled end portion 12 formed with an opening to receive 65 the screw 13 to which the pad 10 is secured.

This arm 11 is provided with an offset portion 14 formed substantially centrally thereof, which offset portion is slightly curved 70 as clearly shown by Figure 3 defining a shoulder to be fitted over the upper edge of the metallic support 15 that provides a finishing structure for the compartment in which the arm 11 moves.

At the upper end of the arm 11 is an offset portion 16 terminating in an upwardly extended finger piece 17, the offset portion 16 providing a shoulder to be engaged by the fingers of the person operating the device. 75

Should it be desired to provide a device of this character wherein the arm 11 may be operated from the front of the door, it will be seen that the arm may be moved to a position as shown in dotted lines in Figure 5, whereupon the arm 11 may operate in an opening formed in the front surface of the door. A stud such as indicated at 10' and having a threaded end 11' may be used for securing the arm 11 to the body 80 portion 8 which stud may be positioned in a suitable recess in the floor to lock the door against movement.

As shown by Figure 6, the body portion, which is indicated at 19 may be formed integral with the arm 20 by bending a length 85 of spring metal in a manner as shown.

In this showing, a pad 21 is provided, and the arm is formed with offset portions 22 and 23 corresponding with the offset portions of the arm as previously described and to accomplish purposes as previously described. 100

From the foregoing it will be seen that when the arm is moved to a position as shown in full lines in Figure 3 of the drawings and the shoulder 22 is positioned over the upper edge of the section 15 of the finishing structure, the door check will be held in its inactive position, but when it is desired to release the same, the arm may be 105 pressed inwardly disengaging the shoulder 110

22 and member 15, whereupon the spring body portion 19 will move downwardly to engage the floor, to hold the door in an open or partially opened position.

5 In the modified form of the invention as illustrated by Figures 7 and 8 of the drawings, the door to which the check is supplied, is provided with a bore extending from the lower edge thereof, the bore being 10 of a diameter to receive the barrel 24 in which the plunger 25 moves, the plunger being tubular in formation and having one of its walls out to provide an arm 26.

As clearly shown the arm 26 is formed 15 with offset portions 27 and 28 for locking the plunger against movement. Mounted within the barrel 24 and disposed between the plunger and upper end of the barrel is a coiled spring 29 that acts to force the

plunger outwardly from the lower end of 20 the barrel. Formed on the lower end of the plunger is a pad 30 that engages the floor under the action of the spring 29 to hold the door equipped with the check in a predetermined position. 25

I claim:

In a door check of the class described, a body portion formed of spring material, an arm at one end of the body portion, said arm having offset portions defining shoulders, and means cooperating with the shoulders for holding the body portion in its inactive position. 30

In testimony that I claim the foregoing as my own, I have hereunto affixed my signature. 35

JOHN H. MAURER.
